UNITED STATES PATENT OFFICE.

FREDERIC H. EHNTS, OF GERMANTOWN, PENNSYLVANIA, ASSIGNOR, BY MESNE ASSIGNMENTS, TO H. W. BUTTERWORTH & SONS COMPANY, A CORPORATION OF PENNSYLVANIA.

WASHING MACHINE.

Original application filed March 23, 1921, Serial No. 454,744. Divided and this application filed June 16, 1925. Serial No. 37,417.

This invention relates to new and useful improvements in machines for washing, dyeing or liquid treating fabrics and similar materials, more especially in some of its details to improvements in machines of this character of the type employing a drum receiver.

The subject matter of the present application is divided from applicant's prior application for washing machines, Serial No. 454,744, filed March 23, 1921, patented September 8, 1925, No. 1,552,599.

It is a general object of the invention to improve and perfect machinery of the character mentioned so as to increase the convenience in handling the stock or material under treatment, preventing injury to the latter, while effectually subjecting all parts thereof to uniform treatment.

Another object of the invention is to provide a machine of the class mentioned with a novel receiver drum construction which is provided with an improved means for subjecting the stock to a squeezing and turning action, while effectually preventing tearing or other injury thereto.

Still another object is the provision, in a machine of the class mentioned, of a novel receiver drum construction which is fitted with a simple and effective means for lifting the stock from the treating liquor and supporting it in position for convenient removal from the receiver.

Other objects will be in part obvious in connection with the following detailed disclosure and in part pointed out therein.

For a more complete understanding of the nature and objects of the invention and for a detailed disclosure of the construction and operation of a preferred embodiment thereof in the form of a washing machine, reference is had to the accompanying drawing forming a part of this specification, and in which

Fig. 1 is a transverse vertical section through the tank and receiver drum of a washing machine embodying the invention, the section being located between the heads of the receiver drum, and certain elements being shown diagrammatically in dot and dash outline for clearness of disclosure.

Fig. 2 is a transverse vertical section sim-

ilar to that of Fig. 1 looking in the same direction with reference to the washing machine as in Fig. 1, the section being located on a plane just inside the end wall of the tank and between said end wall and the end wall of the receiver drum and showing said drum with certain operating mechanism thereon in end elevation; and

Fig. 3 is a fragmentary longitudinal sectional view taken approximately on the line 3-3 of Fig. 1 and showing a plan of the lifting and squeezing diaphragm.

Referring particularly to the drawing, the supporting framework of the machine is indicated generally at 10 and may be of any suitable construction adapted for supporting a tank or receptacle 11 preferably rectangular in plan and having vertical side walls and end walls and a curved bottom merging into the side walls. This tank is adapted for containing the treating liquid, such for example as suds or dye, and may be constructed of suitable material, as wood or noncorrosive metal, and may be supplied with draining and filling conduits, and with other fittings, disclosure of which is unnecessary to an understanding of this invention.

Within the tank 11 is supported a container or receiver 12 which as shown is preferably in the form of a cylindrical drum mounted for rotation on its longitudinal axis, being carried by trunnions or stub shafts 13 projecting from the circular heads or ends 14 of the drum, and in turn supported for rotation in suitable bearings, which may be carried by the end walls of the tank, so that the drum is wholly or partially immersed in the treating liquor of the tank 11. The shell or peripheral side walls of the drum may be provided with perforations 15 for permitting free circulation of the liquor into the interior compartment of the drum, and has a receiving opening 16 through which the stock may be charged into the receiver or discharged therefrom, closures 17 being provided, curved to conform to the contour of the receiver shell and hinged thereto, as indicated at 18. Any suitable securing device or latch, as indicated at 19, may be provided to secure these closures or doors 17 in closed position.

Bearing members 20 are secured to the

outer faces of the receiver heads, being preferably elongated, extending from the center of the drum radially and terminating near the periphery thereof, as shown in Fig. 2, 5 and forming at the inner ends thereof supports for the trunnions 18.

A movable stock manipulating member or stock manipulator 21 is mounted for movement across the interior compartment of the 10 receiver drum, so as to squeeze and agitate or turn the stock therein and to lift it toward the receiving opening of the drum. As shown, this stock manipulator is preferably mounted on a rock shaft 22 extending longitudinally of the drum, and eccentrically disposed therein adjacent the peripheral shell, being extended at one or both ends through the heads of the drum and supported in the outer ends of the bearing members 20.

20 In the embodiment of the invention herein disclosed, the stock manipulator 21 is cylindrical in shape conforming to the cylindrical contour of the drum, preferably extending to or approximately to the heads of the latter. It may be constructed of suitable material, such as cast or sheet metal, having perforations 23 corresponding with the perforations 15 of the receiver drum, and extending about 120° circumferentially. The 25 cylindrical shell of the receiver drum is omitted or cut away, forming a peripheral break or opening 20^a therein adjacent the stock manipulator, and in longitudinal and transverse extent approximately equaling 30 that of the stock manipulator. The stock manipulator is mounted on its supporting rock shaft 22 by means of arms 24 preferably forming stiffening ribs extending transversely of the stock manipulator and positioned so the stock manipulator when swung outwardly falls into and fills the opening or break in the shell of the drum, forming in such position a continuation of the shell conforming to the general cylindrical contour thereof. 35 At its free end the stock manipulator may have an off-set flange 25 adapted to contact with the adjacent inner edge of the shell to limit outward swinging movement of the stock manipulator, and stops 26 secured to 40 the exterior of the drum may be provided if desired for additional support for the free edge of the stock manipulator. Baffle members 27 may be secured to the interior of the stock manipulator, extending longitudinally thereof parallel to each other and acting as supports to carry the material under treatment along with the stock manipulator 21 when the latter is on the ascending side of the receiver. 45

50 It is of advantage to provide the receiver drum with a guard wall 28 positioned to lie adjacent the free or swinging edge of the diaphragm. As shown this guard wall may form a part of the shell of the drum, and 55 includes a perforated wall curved on an arc

concentric with the rock shaft 22, and extends longitudinally of the drum throughout the extent of the stock manipulator 21.

It will be observed that this guard wall extends between the charging opening 16 70 of the receiver and the free edge of the stock manipulator 21 when swung completely outwardly. Said guard wall thereby not only serves as a guard to prevent the stock or goods from falling over the edge 75 of the swinging stock manipulator 21, thus preventing tearing or other injury to the goods and avoiding obstruction to the movement of the stock manipulator, but also functions as a slide against which the stock 80 manipulator 21 operates, thus serving to cause the contents of the receiver to be deflected onto said stock manipulator.

An operating lever 29 is fixed on a projecting end of the rock shaft 22 lying externally 85 of the head 14 of the receiver and between said head and the end wall of the tank 11, being provided at its swinging end with an operating cam roller 30.

On the end wall of the outer receptacle 90 or tank 11 and inside the latter is arranged and supported a cam bar 31 which is pivoted at one end to said end wall as indicated at 95 32, near one vertical edge of the end wall, and preferably below the axis of rotation of the receiver, said cam bar extending upwardly from its pivot in an inclined direction and above the axis of rotation of the receiver. This cam bar is limited in its downward movement by means of a stop lug 100 33 mounted on the tank 11. The movement of the cam bar upwardly away from the stop 33 is yieldingly restrained by a contractile spring 34, one end of which is connected to the free end of the cam bar, while 105 the other end is anchored to a pin 35 fixed to the adjacent end wall of the tank. The cam bar 31 is provided on its underside with a bearing face, being formed preferably adjacent the pivot 32 with a concave portion 110 36 merging into a convex portion 37 at the central portion of said bar, which in turn merges into a concaved portion 38 adjacent the swinging end of the bar. The cam bar 31 and its pivot 32 are so located and arranged that the roller 30 on the lever 29 will engage the cam face of the bar 31 inside said pivot after the free end of the stock manipulator 21 has passed said pivot, thereby 115 causing the stock manipulator to swing inwardly toward the axis of the receiver, either throwing the contents toward the opposite side of the receiver and downwardly into the liquid, or squeezing said contents against 120 said opposite side, provided the bulk of the contents is sufficient. This action of the stock manipulator also effects agitation and 125 turning of the contents of the receiver, thereby subjecting the mass thereof to equalized treatment throughout, enabling the treating 130

liquid to reach all parts thereof, and facilitating dislodgment of dirt and impurities.

In order to prevent the stock manipulator 21 from falling over when its free end passes 21 a vertical line through the rock shaft 22, and also to cause the stock manipulator to move outwardly to its normal outer position 5 into the break 20^a in the receiver shell, a second cam bar 39 may be provided, being 10 preferably fixed to the adjacent end wall of the tank and positioned just below the cam bar 31, providing a passageway between the two bars for the cam roller 30.

The cam bar 39 is located for a major portion 15 of its length with its bearing face substantially parallel to the adjacent face of the bar 31, the initial end of bar 30 being located short of the pivot 32 of bar 31, and the final end being turned away from cam bar 31 and directed downwardly as indicated 20 at 40. By means of this arrangement, when the receiver is revolved in a counter clockwise direction from the position shown in full lines in Fig. 1, the roller 30 strikes the 25 cam bar 31 adjacent the pivot 32, and rides against the bearing face thereof until the upper end of the stock manipulator approximates the vertical, and then upon continued rotation of the receiver, the roller 30 strikes 30 against the cam bar 39, thus holding the stock manipulator in its outer position until the roller passes the center of the receiver, whereupon the continued rotation causes the roller to travel between said cam bars until 35 the roller reaches the down-turned part 40, thereby causing the stock manipulator to resume its normal position in the outer periphery of the receiver. Inasmuch as the section of Fig. 1 is taken inside of the receiver 40 drum head appearing in Fig. 2, and the operative elements upon the outside of said drum head, therefore, do not normally appear in Fig. 1, it is well to observe that in the showing of Fig. 1 the positions of the cam bars 45 31 and 39, and of the operating lever 29, and the lifting member 41 described below, are indicated diagrammatically in dot-and-dash outline for the purpose of showing more clearly the relative position of these parts 50 and other operative elements during the progress of rotation of the receiver drum. During revolution of the receiver, the movement of the stock manipulator just described may vary, due to variations in the load or 55 charge in the receiver, this variation in movement being automatically compensated by virtue of the yielding of the cam bar 31 permitted by the spring 34. It will be understood that the cycle of operations just 60 described is repeated at each revolution of the receiver drum.

It will be observed that rotation of the receiver will result in tumbling and agitation of the stock and liquor therein, effectually dislodging and removing dirt and 65

impurities from the stock, but this is accelerated by the oscillatory action of the stock manipulator, as described.

In addition to the means for automatically swinging the stock manipulator 21, it 70 is desirable also to provide means for manually swinging or lifting it so it may be employed to lift the material under treatment out of the treating liquor and toward the charging opening 16, so it may be conveniently reached for removal from the receiver. A mechanism may be provided for accomplishing this function including a lifting bar 41 fulcrumed at 42 on an end wall of the tank 11, and extending between this end wall 80 and the adjacent head 14 of the receiver. The lifting member 41 is arranged to swing in a vertical plane intersecting the roller 30, and is rigidly connected to a manual operating lever 43 for swinging the lifting bar on its fulcrum. When the receiver is substantially in the position shown in full lines in Fig. 1, the stock manipulator 21 may be swung manually substantially to the position indicated in dot and dash lines in 90 this figure. This is accomplished by swinging the hand lever 43, causing the lifting member 41 to contact with the roller 30, thus causing rotation of the rock shaft 22 and corresponding movement of the stock 95 manipulator.

It will therefore be seen that the stock manipulator may be utilized as a lifting device to lift the goods or stock under treatment out of the liquid and to hold it in a position where it may be conveniently grasped by the operator and removed from the receiver. This is an additional convenience, since the hands of the operator need not be 100 immersed in the liquid in order to remove 105 the contents of the receiver.

Since certain changes may be made in the above construction and different embodiments of the invention could be made without departing from the scope thereof, it is 110 intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a machine of the character described, 125 in combination, a receiver having a substantially closed compartment for the reception of stock and having a receiving opening leading thereto and a gap in the peripheral wall thereof, said receiver being mounted for 130

- movement to agitate said stock, a lifting member mounted for movement within said receiver and positioned to lie when moved outwardly in said gap in the periphery of 5 the receiver so as to form a part of the wall thereof, and means to operate said lifting member to move said stock toward said receiving opening and to support it in position for convenient removal therethrough.
- 10 2. In a machine of the character described, in combination, a receiver including a revolvably mounted drum having a compartment for the reception of stock and having a gap in the wall thereof, a swinging stock 15 manipulator mounted within said compartment eccentrically to the drum mounting and adapted for agitating said stock, and when swung outwardly lying in position to fill said gap in the receiver wall and completing the receiver wall, and the inner surface of said drum adjacent the swinging edge of the stock manipulator being formed 20 to lie closely adjacent to said edge throughout its swinging travel so as to prevent said edge of said stock manipulator from injuring said stock and to prevent the stock manipulator from being obstructed in its movement by the stock.
3. In a machine of the character described, 25 in combination, a receiver drum having an interior compartment and a receiving opening leading to said interior compartment and said drum having a gap therein apart from said receiving opening and being revolvably mounted to agitate the contents of the receiver, a swinging stock manipulator mounted within said receiver eccentrically to the receiver mounting and conforming in contour to the sides of the receiver drum and in one position lying in said gap in the receiver drum to complete the wall thereof, and manually operable means to move said stock manipulator so as to lift the contents 40 of the receiver toward said receiving opening and to hold it in position for convenient removal therethrough, the receiver having a curved wall portion approximately concentric with the mounting of said stock manipulator and lying adjacent the swinging edge thereof.
4. In a machine of the character described, 45 in combination, a receptacle for a treating fluid, a receiver drum revolvably mounted in said receptacle and providing a substantially closed receiver having a compartment for the reception of stock and having a receiving opening leading to said compartment and a gap in the wall thereof, a swinging stock manipulator mounted within said 50 compartment and conforming in contour to the wall of said receiver and positioned to lie in and fill said gap in the receiver wall, and means to move said stock manipulator to lift said stock toward the receiving open-
- ing and support it in position for convenient removal therethrough. 65
5. In a machine of the character described, in combination, a receiver having an interior compartment for containing stock under treatment and having an opening leading to 70 said interior compartment and a gap remote from said opening, said receiver being mounted for operation to agitate said stock, a lifting member mounted in said receiver and in one position lying in said gap to complete the walls of said receiver, and means to move said lifting member to lift the stock contained in the receiver toward said opening and to hold it in lifted position. 75
6. In a machine of the character described, 80 in combination, a receiver having a charging opening and a second opening remote from said charging opening, a stock manipulator pivotaly mounted within said receiver and when in outward position lying within 85 said second opening, a lever connected to said stock manipulator and extending outside the receiver, and a manually operable lever cooperable with said first named lever to move said stock manipulator to lift the 90 contents of the receiver toward said charging opening.
7. In a machine of the character described, 95 in combination, a rotary receiver having a charging opening and a second opening remote from said charging opening, a swinging stock manipulator in said receiver and when in outward position lying within said second opening, means cooperable with said stock manipulator to automatically swing it 100 during rotation of the receiver, and manually operable means to move said stock manipulator to lift the contents of the receiver toward said charging opening. 105
8. In a machine of the character described, 110 in combination, a rotary receiver having a compartment for the reception of stock with a receiving opening leading thereto and a second opening remote from said receiving opening, a rock shaft extending longitudinally of said receiver, a stock manipulator rigidly mounted on said rock shaft and in one position lying within said second opening of said compartment so as to form a part 115 of the wall of said receiver, means for automatically rocking said shaft during rotation of the receiver, and manually operable means independent of said first mentioned means for rocking said shaft.
9. In a machine of the character described, 120 in combination, a rotary receiver having a compartment for the reception of stock including a shell and heads and having a receiving opening leading to said compartment and a second opening remote from said 125 receiving opening, a rock shaft extending longitudinally of the receiver and mounted in bearings in said heads, a stock manipu-

lator mounted on said rock shaft and in one position lying substantially wholly on one side of said compartment and closing said second opening, a lever on said rock shaft, a yielding cam bar engageable by said lever during a period of a revolution of said receiver to rock said stock manipulator, and an independent manually operable means cooperating with said lever to rock said stock manipulator.

10. In a machine of the character described, in combination, a receiver having a receiving opening and a second opening remote from said receiving opening, a rock shaft extending longitudinally of the receiver, a stock manipulator mounted on said shaft and in one position lying in said second opening to form a wall of the receiver, and manually operable means for said shaft.

11. In a machine of the character described, in combination, a rotary receiver having a receiving opening and a second opening remote from said receiving opening, a rock shaft extending longitudinally of the receiver, a stock manipulator mounted on said rock shaft and in one position lying within said second opening and forming a part of the wall of the receiver, means for automatically rocking said shaft during rotation of the receiver, and manually operable means for operating said rock shaft.

12. In a machine of the character described, in combination, a rotary receiver having a receiving opening and a second opening remote from said receiver opening, a rock shaft extending longitudinally of the receiver, a stock manipulator mounted on said rock shaft and in one position lying in said second opening and forming a part of the receiver wall, a lever attached to said rock shaft, and manually operable means cooperating with said lever to move said rock shaft and swing said stock manipulator to lift the contents of the receiver toward said receiving opening.

13. In a machine of the character described, in combination, a receptacle, a rotary receiver within said receptacle including heads and a shell having an opening therethrough, a stock manipulator mounted for swinging movement within said receiver and in one position lying within said opening and forming a part of the wall of the receiver, an operating lever connected to said stock manipulator, a yielding cam bar engageable by said lever during a period of a revolution of said receiver to swing said stock manipulator, and manually operable

means cooperable with said lever when the latter is out of engagement with said cam bar to swing said stock manipulator.

14. A rotary receiver drum for machines of the character described, having a compartment for the reception of stock and an opening in the periphery thereof leading into said compartment, a stock manipulator mounted for movement within said compartment and when in one position lying in said opening in the periphery of the drum and forming a part of the wall for the latter.

15. A rotary receiver drum for machines of the character described, having a compartment for the reception of stock and an opening in the periphery thereof leading into said compartment, a stock manipulator mounted for swinging movement within said compartment and when in one position lying in said opening in the periphery of the drum and forming a part of the wall for the latter, and the drum having a wall section with the inner surface thereof disposed adjacent the swinging edge of the stock manipulator and curved concentrically with the mounting of said stock manipulator.

16. A rotary receiver drum for machines of the character described, having a compartment for the reception of stock with a receiving opening leading thereto and a second opening remote from said receiving opening, a stock manipulator mounted for movement within said compartment and when in one position lying within said second opening and forming a part of the wall for the receiver and being movable toward said receiving opening to lift the stock and to support it in convenient position for removal.

17. A rotary receiver drum for machines of the character described, having a compartment for the reception of stock with a receiving opening leading thereto and a second opening remote from said receiving opening, a stock manipulator mounted for swinging movement within said compartment and in one position lying in said second opening and forming a part of the wall for the compartment, and swingable toward said receiving opening to squeeze the stock and to lift and hold it in convenient position for removal, and said drum having a wall section with inner surface thereof adjacent the swinging edge of the stock manipulator and being curved concentrically with the mounting of said stock manipulator.

In testimony whereof I affix my signature.

FREDERIC H. EHNTS.
